UNITED STATES PATENT OFFICE.

ALEXANDER HEMSLEY, OF PHILADELPHIA, PENNSYLVANIA, ASSIGNOR TO
LUCIEN C. OVERPECK, OF HAMILTON, OHIO.

APPARATUS FOR PRODUCING INSTANTANEOUS FLASH-LIGHT.

SPECIFICATION forming part of Letters Patent No. 426,411, dated April 22, 1890.

Application filed May 8, 1888. Serial No. 273,163. (No model.)

To all whom it may concern:

Be it known that I, ALEXANDER HEMSLEY, a citizen of the United States, residing at the city of Philadelphia, in the county of Philadelphia and State of Pennsylvania, have invented certain new and useful Improvements in Apparatus for Igniting Materials and Producing an Instantaneous Artificial Flash-Light Applicable to Photographic Purposes, 10 of which the following is a specification.

My invention has relation to apparatus applicable to instantaneous photographic and other purposes.

The principal objects of my invention are, 15 first, to provide a device or apparatus with a stationary or removable shallow vessel or receptacle for holding a material capable of ignition and with means whereby a flame in the form of a jet may be caused to ignite said material and thereby produce an incandescent artificial flash-light especially applicable to instantaneous photography, and, second, to provide the device or apparatus with a burner located in close proximity to said shallow vessel, and with a reflector capable of adjustment, located in the rear thereof, in order to enable the operator to properly focus the figure or object to be translated and to enable him to determine with greater accuracy or certainty how the shadows are falling, whereby 25 the artistic effect of the photograph will be appreciably enhanced.

My invention will be more particularly understood taken in connection with the accompanying drawing, illustrating in perspective my improved device or apparatus in a form which has been found practically efficient for the purpose.

Referring to the drawing, A is an oblong 35 table made of brass, copper, or other material, provided with a shallow vessel or receptacle a for containing material to be ignited.

B is a gas-admission pipe onto which the table A is secured. To the upper extremity 45 of the pipe B is rigidly secured a fitting c, provided with an ordinary valve-cock c', for shutting off the gas forced through the pipe B and small orifices in the fitting c. A curved or other form of pipe d, with a tapering extremity to produce a jet-flame, is secured into

the fitting c and is in direct communication with an orifice formed in the fitting c. Gas in sufficient quantity is allowed to escape around the valve-cock c' to permit of the lighting of the same at the end of the pipe d and to keep a flame thereat while the gas is being forced upward through the pipe B and the attachments secured thereon, and onto which the burner is fitted, in a manner to be presently explained.

Rigidly secured to the fitting c is a T-fitting d', with a central orifice extending upward through the same for the passage of gas, and to which fitting is attached a swinging fixture or bracket D, with a valve-stem with 65 orifices therein, and which stem is held to place in the fitting d' by means of a washer d² and nut d³. This swinging fixture or bracket D has a freedom of movement in the fitting d', whereby the position of the single 70 or duplex burner d⁴, attached to the free extremity of said fixture, may be adjusted to any desired angle or position for properly focusing and determining with accuracy or certainty how the shadows will fall in the photograph.

To the head of the stop-cock c' is rigidly secured an oscillating lever f, extending downward through an oblong slot a' in the table A. This lever is pivoted to a bifurcated longitudinal rod f', provided with a piston-head f². The longitudinal rod f', pivoted to the oscillating lever f, is caused to move back and forth in a cylinder F, supported to the under side of the table A, by compressing a bulb g, 85 fitted to a section of hose attached to a pipe g', secured into the head of the cylinder F.

Mounted on the table A is an inverted L-plate H, with an oblong slot h therein. In the table A is rigidly secured a post h', the upper 90 portion of which is threaded for the reception of a nut h², whereby the plate H may be clamped in a desired position onto the table A to regulate the movement of the longitudinal piston-rod f' forward and backward when 95 actuated by means of the hose and bulb g and the opening and closing of the valve-cock c', which regulates the flow of gas through the pipes B and d to increase or diminish the size of the jet-flame caused to ignite the ma- 100

terial previously placed in the shallow vessel *a* of the table for the production of an artificial flash-light and as well the size of the flame at the burner *d* in close proximity to 5 the receptacle or shallow vessel *a*.

Rigidly secured to the rear of the table *A* is a sleeve *m*, with a tightening-screw *m'*. Through this sleeve a vertical rod *n* is inserted and held in any desired position vertically by means of the tightening-screw *m'*. The upper extremity of the vertical rod *n* is provided with a tongue *n'*, which is fitted between two jaws *o* and *o'* of a bracket *O*, secured to the back of a reflector *P* of any suitable construction. The reflector *P* may be set at any desired angle by means of an adjusting-screw *p*, passing through the jaws *o* and *o'* of the bracket *O* and the tongue *n'* of the vertical rod *n*. A standard *E*, provided 20 with a socket *e*, is fitted onto the gas-pipe *B* and supports the apparatus hereinbefore described by means of the set-screw *e'* in any desired vertical position. The gas-pipe *B* is connected with a source of supply by means 25 of rubber tube *b*, and the apparatus may be thereby set at any desired height by simply increasing the length of the pipe *B* and the rubber tube *b*.

Having described and pointed out the characteristic features of my improved apparatus, 30 I will now proceed to briefly explain the mode of operation thereof for causing a material or compound to be ignited for producing an instantaneous flash-light especially applicable 35 to photographic purposes.

The table is first elevated to the position desired, with the reflector *P* set to the angle and height for causing the best results to be obtained. The gas-burner *d* and the jet-40 pipe *d* are then lighted by the attendant and the material to be ignited placed in the shallow vessel or receptacle *a* of the table *A*. The rubber bulb *g*, in connection with a section of hose attached to the pipe *g'*, extending 45 through the head of the cylinder *F*, is compressed, thereby forcing the air against the piston and causing the longitudinal piston-rod to be moved forward, actuating the oscillating lever *f* and opening the valve *c'*, and causing a flame at the end of the pipe *d*, in the form of a jet, to be communicated 50 to the material or compound capable of being readily ignited in the shallow vessel *a*, producing instantly an incandescent flash-light for photographic and other purposes. 55 By releasing the pressure exerted on the bulb *g* the piston will be retracted, thereby partially closing the valve *c'* and diminishing the size of the flame at the extremity of the 60 pipe *d*.

I do not wish to be understood as limiting myself to the use of ordinary gas, as where such is not available the lime or other light may be substituted with equally good results.

65 I do not wish to be understood as claiming as of my invention the combination of a continuous actinic light, an exposed shelf con-

tiguous thereto and adapted to receive a charge of flash material, and means for lighting said charge.

I hereby disclaim as of my invention a device provided with a table containing a shallow vessel for the reception of material to be ignited, a pipe secured to said table for admitting gas to a burner and to a pipe secured 75 to said admission-pipe, and means for causing a flame to be communicated to said material.

Having thus described the nature and objects of my invention, what I claim as new, 80 and desire to secure by Letters Patent, is—

1. A device provided with a table containing a shallow vessel for the reception of material to be ignited, a pipe secured to said table for admitting gas to a burner and to a pipe secured 85 to said admission-pipe, and means for causing a flame to be communicated to said material, substantially as and for the purposes set forth.

2. A device consisting of a table containing a shallow vessel, a pipe for supporting said table and admitting gas to a jet-pipe, a valve in said admission-pipe, and a piston actuated by air-pressure for operating said valve, substantially as and for the purposes 95 set forth.

3. A device consisting of an adjustable table provided with a shallow vessel and an adjustable reflector, a pipe for admitting gas to a burner, and a curved pipe secured into 100 said pipe, and a valve actuated by air-pressure for causing a jet-flame to be produced, substantially as and for the purposes set forth.

4. A device consisting of a table with a shallow vessel and a reflector, a pipe for admitting gas to a burner in close proximity to said vessel and to a pipe located below said burner, a valve in a fitting attached to said pipe, and a piston operated by air-pressure, 110 substantially as and for the purposes set forth.

5. A device consisting of a table provided with a shallow vessel for containing an ignitable material, an adjustable reflector, a 115 pipe for adjustably supporting said table and admitting gas to a burner, and a pipe attached to said admission-pipe and communicating with a valve, and a piston for operating said valve, substantially as and for the 120 purposes set forth.

6. A device consisting of a table provided with a shallow vessel, and a pipe secured to said table and supplying gas to a burner and to a pipe for causing a jet-flame to be produced, a valve opened and closed by an oscillating lever actuated by a piston under pressure, and an adjustable standard for elevating and lowering said table, substantially as and for the purposes set forth.

7. A device consisting of a table provided with a receptacle for containing an ignitable material, a pipe for adjustably supporting said table and supplying an illuminant to a

burner, and a jet-pipe in communication with a valve provided with a lever, and a piston for operating said lever, and means for regulating the back-and-forth movement of said 5 valve, substantially as and for the purposes set forth.

In witness whereof I have hereunto set my

signature in the presence of two subscribing witnesses.

ALEXANDER HEMSLEY.
